UNITED STATES PATENT OFFICE.

ALFRED ALEXANDER LAWSON, OF WINDSOR, ONTARIO, CANADA.

KEY FASTENER.

Application filed May 5, 1922. Serial No. 553,533.

To all whom it may concern:

Be it known that I, ALFRED ALEXANDER LAWSON, a subject of the King of Great Britain, residing at Windsor, in the Province of Ontario and Dominion of Canada, have invented new and useful Improvements in Key Fasteners, of which the following is a specification.

This invention comprehends the provision 10 of what I term a key fastener, and is in the nature of a plate which is pivoted upon the slotted escutcheon, and designed to fit over the key when the shank of the latter is arranged at a right angle to the key-hole slot 15 to prevent the key from being pushed out of the lock from the outside, or turned, thus making it impossible for anyone to unlock the door from the outside. It is also particularly useful in preventing the loss 20 of the key, and the passage of air and drafts through the key-hole slot.

More specifically stated, the invention makes use of a plate having what I term a compound slot opening at one side of 25 the plate, and an elongated slot to receive the pivot for said plate, whereby the plate is mounted for vertical as well as swinging movement, necessitating a number of 30 separate and distinct movements in order to associate the plate with the key or remove the plate therefrom, so that when the plate is positioned over the key, it is impossible for anyone to move the plate off the key from the outside of the door.

The nature and advantages of the invention will be better understood when the following detailed description is read in connection with the accompanying drawing, the invention residing in the construction, 40 combination, and arrangement of parts as claimed.

In the drawing forming part of this application, like numerals of reference indicate similar parts in the several views, and 45 wherein:

Figure 1 is a view in elevation, showing the active position of the plate.

Figure 2 is a similar view, showing one position of the plate just prior to its separation from the key.

Figure 3 is a similar view, showing the plate wholly removed from the key.

Figure 4 is a detail view of the plate.

Figure 5 is an edge elevation of the plate.

Referring to the drawing in detail, 50

indicates the usual door knob plate provided with a key-hole slot 11, in which I have illustrated the key 12. It will be noted that the key is in the position it occupies when the door (not shown) is 60 locked, and in which position, it is arranged at a right angle to the slot 11.

It is in order to hold the key in this position, so as to prevent it from being removed from the outside of the door, or turning from 65 the outside of the door in an effort to unlock the latter, that I provide what I term a key fastener, the latter being clearly illustrated in Figure 4.

The key fastener consists of a plate 14 70 which may vary in size and configuration without departing from the spirit of the invention, and which plate is adapted to be pivoted upon the plate 10 at an appropriate point above the key-hole slot 11. The pivot 75 of the plate 14 is indicated at 15, and is received by an elongated slot 16 provided in the plate 14 adjacent the upper end thereof. The plate 14 is also provided with what I term a compound slot which is arranged 80 substantially at a right angle to the slot 16, and opens at one side of the plate as clearly shown. The compound slot includes a reduced portion 17, this portion constituting the closed end of the slot, and which portion 85 opens into an enlarged intermediate portion 18, which is shaped to provide the opposed shoulders 19 and 20 respectively. The intermediate portion 18 of the slot opens into the reduced section 21.

In practice, after the door above referred to has been locked through the instrumentality of the key 12, the latter occupies the position with relation to the key-hole slot as illustrated. The plate 14 is then arranged in 95 the manner shown in Figure 1, wherein the shank of the key is received by the reduced portion 17 of the slot. It will be noted that when the plate is in this position, the elongated slot 16 for the pivot 15 is arranged at 100 an inclination to the shank of the key and should the plate 14 be swung upon its pivot in an effort to separate the plate from the shank of the key, the slot 16 would be brought to a vertical position allowing the 105 plate to drop a short distance in order to position the shoulder 19 at one side of the shank of the key, and this shoulder 19 would prevent the plate from being moved on its pivot. Consequently, the plate could not at 110

- any time be separated from the shank of the key, by anyone operating from the outside of the door. It is obvious that in order to separate the plate 14 from the shank of the key, 5 the plate must be swung upon its pivot from the position illustrated in Figure 1 to the position shown in Figure 2, and then the plate must be moved vertically in order to move the shoulder 19 above the shank of the key, this movement of the plate being permitted by the elongated slot 16, and the plate can then be further swung upon its pivot to wholly separate the plate from the key as 10 will be readily understood.
- 15 While it is believed that from the foregoing description, the nature and advantages of the invention will be readily apparent, I desire to have it understood that I do not limit myself to what is herein shown and 20 described, and that such changes may be resorted to when desired as fall within the scope of what is claimed.

What I claim is:—

The combination with a plate having a key-hole slot, of a key fastener comprising 25 a plate pivoted on the first mentioned plate for swinging movement, the movable plate having a compound slot opening at one side thereof, and adapted to receive the shank of the key when the latter is positioned within the slot of the first mentioned plate, a shoulder defined by the compound slot and arranged to prevent the movable plate from being removed from the key incident to the swinging movement of the plate in one direction, and said movable plate having an elongated slot for the reception of the pivot therefor, whereby said plate is permitted to be moved vertically to move said shoulder out of the path of said key as and for the 30 40 purpose specified.

. In testimony whereof I affix my signature.

ALFRED ALEXANDER LAWSON.
